UNITED STATES PATENT OFFICE.

ALOYSIOUS J. KINNANE, OF KNOXVILLE, TENNESSEE.

BOILER-FLUE FERRULE.

1,252,585.

Specification of Letters Patent.

Patented Jan. 8, 1918.

Application filed May 24, 1916. Serial No. 99,861.

To all whom it may concern:

Be it known that I, Aloysious J. KINNANE, a citizen of the United States, residing at Knoxville, in the county of Knox and 5 State of Tennessee, have invented a new and useful Improvement in Boiler-Flue Ferrules, of which the following is a specification, reference being had to the accompanying drawing.

10 My improvement relates particularly to means for securing the ends of the flues of tubular boilers in the flue sheets.

The object of my improvement is to reinforce the ends of the flue tubes for the purpose of adding strength thereto and also to form a seal between the end portions of the tubes and the adjacent sheet. A further object of the improvement is to shield the end portions of the tubes from the destructive 20 physical and chemical action of the combustion products passing through the flues.

My improvement may be applied to new steam boilers while they are being built, or it may be applied to individual tubes as leakage may make demand from time to time.

In the accompanying drawings,

Figure 1 is a side elevation of a member used in applying my improvement, a portion of said member being broken away;

30 Fig. 2 is an elevation looking toward the right of Fig. 1, a portion being broken away;

Fig. 3 is a section along the axis of a tube showing one end of the tube in position in a sheet and having my improvement applied thereto;

Fig. 4 is an elevation of a portion of a sheet with my improvement applied thereto, a portion being broken away;

40 Fig. 5 is a detail section illustrating another form of the construction.

Referring to said drawings, 1 is a part of a flue sheet of a tubular steam boiler of any ordinary form, and 2 is a flue tube of ordinary form and having one end resting in an 45 aperture, 3, in said sheet. Outside of the sheet, the tube has a bead or flange, 4, of ordinary form bearing against the outer face of the sheet. A shoulder, 5, on the tube, engages the inner face of the sheet, so that the 50 sheet is engaged by the bead or flange, 4, and the shoulder, 5.

The tube may be inserted and flanged in the flue sheet in the usual manner by means of tools suited to this purpose.

55 It is well-known, that, in the use of such boilers, leakage occurs between the sheet and

the end of the tube, and that it is difficult to remedy this defect. Such leakage may be due to thermal expansion or contraction, to mechanical strains put upon these parts by 60 steam pressure or otherwise, or to corrosion or burning of the metal of the flue at the end of the latter.

My improvement consists in applying to the tube and the end of the sheet the reinforcing member, 6, shown by Figs. 1 and 2. Said member comprises a tubular body, 6^a, and a flange, 6^b, the tubular body being cylindrical and of as large exterior diameter as will permit sliding endwise into the tube, 70 2, while the flange, 6^b rests on the flange, 4, of the tube, 2. The edge of the flange, 6^b, is preferably tapered as shown. The inner edge of the body, 6^a, is also preferably tapered or reduced in thickness, as shown. 75

When the member, 6, has been moved into the flue, 2, as far as permitted by the flange, 4, the inner edge of the tubular body, 6^a, is welded to the inner face of the flue, 2, along the area, 7, and the flange, 6^b, of the member, 6, is welded to the flange, 4, and to the outer face of the sheet, 1, by means of a welding metal, 8, applied by fusion to the said three members. Thus said three members and said mass of welding metal, 8, are 80 effectively united into substantially a single mass affording ample strength and stability.

In the manufacture of new boilers, the flue, 2, may be secured in the sheet, 1, in the usual manner and with the usual care, with 90 a view to avoiding leakage. The member, 6, may then be inserted and secured within and outside the flue, as above described.

When thus secured, the member, 6, serves in several ways: (a) by reducing strains on 95 the flue and the sheet relative to each other; (b) the adjacent end portion of the flue is protected against the chemical and physical action of the highly heated combustion products passing through said flue, such action, 100 when not prevented reducing said tubes by corrosion or burning or abrasion, until the tube has been weakened to such extent as to cause yielding away from the sheet and thus permitting leakage or to form places in 105 the flue wall so thin as to permit water or steam in the boiler to break through; (c) by preventing the escape of steam or water from the boiler, even when there is leakage at the sheet opening in which the tube rests. 110

While the welding area may be extended to any desired degree, it is preferable to do

such welding only along the edges of the reinforcing member, leaving other portions of said member free from the tube, in order that heat absorbed by the reinforcing member 5 will be less rapidly transmitted to the flue, and in order that expansion and contraction and strain in the reinforcing member or in the flue will to the smallest degree affect the companion member.

10 If my improvement is applied only for the purpose of stopping leaks in boilers already in service, the member, 6, is applied, in the manner already described, at the end of any flue at which there is leakage and 15 which has undergone such deterioration as to make mending by the use of expanding and beading tools difficult or impossible. It will be observed that in such cases defects in the flue and in the sheet, 1, between the weld 20 areas, 7, and 8, are substantially immaterial; for the reinforcing member, 6, forms a supplemental wall between said areas.

The member, 6, is preferably made of a metal differing from the metal of the flue 25 and the sheet, for example, a variety of cast iron which is strong and which at the same time expands and contracts to a minimum degree under thermal variations.

The welding may be performed by the aid 30 of heat produced by electricity or by means of gas flames adapted to produce high temperature.

The wall of the body, 6^a, is made as thin 35 as the demand for strength permits, in order that the caliber of the flue will be reduced as little as possible.

When the improvement is to be applied to new boilers, the portion of the flue adjacent to the sheet may be increased in diameter by 40 forming an offset, 9, around the wall of the tube, as shown in Fig. 5, the body, 6^a, of the reinforcing member, 6, then lying in the enlarged portion of the flue and the inner face of said reinforcing member being approximately flush with the inner face of the flue beyond the offset, 9, and the inner edge of said body extending preferably to said offset, so that the weld area, 7, will be formed at said offset. When the reinforcing member 45 is to be applied to boilers already built, the ends of the flues may be enlarged through a distance equaling the length of said member, as described in this paragraph relative to new boilers, by the use of expanding tools 50 before the reinforcing member is inserted.

In present practice, a bushing or sleeve of soft copper is put around the flue within the sheet. Usually the firm union made by welding the flanges, 6^b, and 4, and the sheet, 1, to each other will render the copper bush- 60 ing unnecessary.

I claim as my invention,

1. The combination with a flue sheet and a flue extending through said sheet and having a bead at its outer end, of a reinforcing 65 member entering the flue and having a flange extending partially across said bead, and a mass of welding metal fused to said flange and the bead of the flue and to the outer face of the sheet, substantially as described. 70

2. The combination with a flue sheet and a flue extending through said sheet and having a bead at its outer end, of a reinforcing member entering the flue and having a flange extending partially across said head, and 75 having its inner end welded to the flue, and a mass of welding metal fused to said flange and to the bead of the flue and to the outer face of the sheet, the intermediate portions of said reinforcing member being left free 80 from the flue, substantially as described.

3. The combination with a flue sheet and a flue extending through said sheet and having a bead at its outer end, of a reinforcing member composed of a metal differing from 85 the metal of the flue and the sheet and entering the flue and having a flange extending partially across said bead, and a mass of welding metal fused to said flange and to the bead of the flue and to the outer face of the 90 sheet, substantially as described.

4. The combination with a flue sheet and a flue extending through said sheet and having an enlarged portion and a bead at its outer end, of a reinforcing member entering the 95 flue and resting in said enlarged portion and having a flange extending partially across said bead and having its inner end welded to the flue, and a mass of welding metal fused to said flange and to said bead of the 100 flue and to the outer face of the sheet, the intermediate portion of the reinforcing member being free from the flue, substantially as described.

In testimony whereof I have signed my 105 name, in presence of two witnesses, this 20th day of May, in the year one thousand nine hundred and sixteen.

ALOYSIOUS J. KINNANE.
